IRON SUPPORTING LINKAGE

Edwin E. Foster, Austin, Tex., assignor to Majik-Ironers, Inc., Austin, Tex., a corporation of Texas

Application March 22, 1951, Serial No. 217,026

17 Claims. (Cl. 38—30)

1

This invention relates to supports for irons and more particularly to a linkage for supporting a flat-iron above a board for movement onto the board for ironing and to raise the iron above the board when it is not in use.

In supporting mechanisms of this type, as broadly disclosed for example in my Patents Nos. 2,369,732, 2,345,251, 2,231,896, and in my copending applications Serial Nos. 669,318, filed May 13, 1946 and now abandoned, 25,137, filed May 8, 1948, and 195,860, filed November 15, 1950, now Patent No. 2,555,639, issued June 5, 1951, it is desirable to remove the effect of the spring which acts to raise the iron when the iron is lowered onto the board during ironing. It is one of the objects of the present invention to provide a support which is relatively simple to construct and which functions effectively to remove the raising force on the iron when the iron is lowered to working position.

Another object is to provide a support in which the raising spring can be made effective or ineffective by a latch easily controlled by the operator.

According to one feature, the latch is controlled by an operating lever lying adjacent to and preferably above the iron handle for easily and naturally controlling of the latch by an operator.

Another object is to provide a support in which the raising effect of the spring is balanced by a second spring when the iron is lowered to ironing position and in which the second spring can be made effective or ineffective by a latch.

Still another object is to provide a support in which the effect of the raising spring decreases as the iron is lowered to its normal working position and increases when the iron moves to an extreme lowered position as, for example, when it drops below the board.

A further object is to provide a support in which a lever is employed to connect the supporting linkage to a supporting element and the lever is guided so as to maintain it in proper vertical position at all times.

The above and other objects and features of the invention will be more readily apparent from the following description when read in connection with the accompanying drawing in which:

Figure 1 is a partial side elevation showing an iron and a supporting linkage embodying the invention;

Figures 2 and 3 are sections on the lines 2—2 and 3—3 of Figure 1 respectively;

Figure 4 is a partial section of one supporting linkage showing the iron in raised position;

2

Figure 5 is a section on the line 5—5 of Figure 4;

Figure 6 is a view similar to Figure 4 showing the iron in lowered working position;

5 Figure 7 is a view similar to Figure 4 of an alternative construction;

Figure 8 is a view similar to Figure 7 showing the iron lowered to its normal working position; and

10 Figure 9 is a partial section showing the iron lowered to an extreme position.

As shown in Figure 1, a flat-iron 10 which may be of more or less conventional construction is adapted to be supported for movement above and parallel to an ironing board 11 and to be lowered against material on the board for ironing when desired. The iron is normally carried by a pair of pivotally interconnected levers including a relatively long lever 12 pivoted on a horizontal axis at its lower end on a vertical rod 12' for rotating movement about a vertical axis and for swinging movement about the horizontal axis. A short lever 13 is pivoted to the upper end of the lever 12 and terminates at its lower end in a joint indicated at 14 for connection to the iron supporting linkage. The levers 12 and 13 may be hollow, as indicated in Figures 2 and 3, and the electric cord for supplying current to the iron may pass therethrough as indicated at 14'. In addition, the levers may be interconnected by mechanism as more particularly described and claimed in my copending application Serial No. 669,318, filed May 13, 1946 and now abandoned, so that as the levers pivot between the full and dotted line positions illustrated, the joint 14 will be constrained to move in a plane parallel to the ironing board 11.

40 The iron is connected to the joint 14 through a supporting linkage which forms the subject matter of the present invention. As illustrated in Figures 1—6, the linkage comprises a lower hollow arm 15 formed at its lower end for rigid connection to the iron. As best seen in Figures 4—6, the hollow arm 15 terminates at its lower end in a flange which is secured by a screw 16 to the iron body. The arm 15 forms the forward part of the iron handle as shown at 17 which is secured rigidly to the iron body and is spaced above it to be grasped conventionally by the operator. The handle may be formed of any desired material such as a molded plastic and is preferably hollow with its top open as shown in Figures 4 and 6.

55 The upper end of the arm 15 is pivotally connected at 18 to an upper hollow arm 19. At its

free end the arm 19 carries a pivoted mounting lever 21 terminating in a mounting ball 22 which is engaged in the joint member 14 for universal and rotating movement. In this way the iron can be turned or swung to any desired position during use.

The linkage is normally held in the position shown in Figure 4 to raise the iron above the level of the board, as shown in dotted lines in Figure 1, by means of a spring 23. As shown, the spring 23 is a tension spring anchored at one end to pivot pin 24 for the lever 21 and at its opposite end to a pin 25 rigidly secured in the arm 15. The pin 25 lies below the pivot 18 and is preferably slightly farther from the pin 24 than is the pivot 18. With this construction, when the linkage is straightened to move the iron toward the board, to its working position, the line of the spring moves toward the pivot 18 to shorten the effective moment arm of the spring so that the spring effect tending to raise the iron will be decreased, notwithstanding the increase in tension of the spring 23. Thus, less force is required to hold the iron in its lowered working position than to move it initially from its raised position above the board.

In order to cancel completely or substantially completely the elevating effect of the spring 23, a second spring is provided to oppose the elevating spring and which becomes effective when the iron is lowered. As shown in Figures 4-6, a compression spring of the type which will develop a substantially constant spring force regardless of its degree of compression is employed. This spring is in the form an elongated coil spring 26 having normally contacting adjacent turns and having end portions 27 offset from its axis so that when the spring is compressed it will bow outward as indicated in Figure 6. I have found that a spring of this type will develop a substantially constant degree of force regardless of its degree of compression so that a very desirable effect for use in the compression mechanism is produced.

The upper end portion 27 of the spring 26 is pivoted to an extension on the upper arm 19 which normally lies substantially in line with the pivot 18 and the pin 25, as shown in Figure 4. At its lower end, the spring is pivoted to a movable abutment 28 which is in the form of a plate pivoted at 29 to the arm 15. When the iron is in its raised position as shown in Figure 4, the spring 26 is relaxed and the abutment member will normally lie in the position illustrated. However, when the iron is moved downward, the spring 26 will be compressed and will tend to swing the abutment 28 counter-clockwise about its pivot 29.

In order to hold the abutment plate against swinging to make the spring 26 effective, latch means are provided engaging the abutment 28. As shown, the latch means comprises a latch lever 31 pivoted at 32 to the arm 15 and having an elongated operating handle 33 rigidly secured thereto and lying in the hollow handle 17. The latch operating handle 33 projects above the iron handle 17 where it can easily be engaged by an operator's hand and will be held down by the operator's hand during normal gripping of the iron handle. Preferably the end of the lever 31 is at a slight angle and engages the pin 34 on the abutment plate 28 so that compression of the spring 26 tends to raise the latch handle 33. The force acting on the latch handle can, however, be made very small so that the effort re-

quired to hold the latch handle down can be such that it is unnoticeable to the operator.

In normal use of the iron, the iron will be held above the board at the level shown in dotted lines in Figure 1, with the supporting linkage occupying the position shown in Figure 4. At this time, the spring 26 is ineffective and the spring 23 will hold the linkage in its angular position with the iron elevated. To use the iron the operator grasps the handle 17 thereby automatically engaging the latch handle 33 to hold it in its lowered position and presses the iron toward the board. During this operation, the linkage will move to the position shown in Figure 6 and during the latter part of this movement the spring 26 will be compressed and will exert a turning force on the arm 19 opposing the force on the spring 23. By proper design of the springs, these two forces can be made to balance each other almost exactly and it will be noted that this balance is maintained over a relatively wide range of vertical movement of the iron, due to the fact that the compressive force of the spring 26 is substantially the same regardless of its degree of compression. At this time, the iron can be moved over on material on the board 11 in a normal manner to effect an ironing operation.

When the operator releases the iron handle, the latch handle 33 will swing upward and the latch lever 31 will move away from the pin 34, allowing the abutment 28 to swing counter-clockwise. This will relieve the compressive force of the spring 26, leaving the spring 23 effective to raise the iron above the board. Even though the effective raising force of the spring 23 is at a minimum when the iron is lowered, it is still sufficient to lift the weight of the iron. As the iron starts to move upward, the spring 23 becomes more and more effective to insure raising of the iron to the desired elevated position. Thus whenever the operator releases the iron handle, the latch will be released to make the elevating spring once more effective so that the iron will be raised. This completely eliminates any possibility of the iron being accidentally left on material on the board to scorch or otherwise damage it.

Figures 7-9 illustrate an alternative construction in which parts corresponding to like parts in Figures 1-6 are indicated by the same reference numerals plus 100. In this construction, the spring 123 is anchored at one end to the cross pin 125 on the arm 115 and is adjustably connected at its opposite end to an adjusting screw 135 which extends through the end of the arm 119. The adjusting screw threads into a block 136 in the adjacent end of the spring so that by turning the screw to thread it more or less into the block, the tension of the spring 123 can easily be adjusted to the desired value.

The balancing spring, as illustrated in these figures, comprises a compression spring device including a pair of levers 137 and 138 pivoted to each other and to the arm 115 by a pin 139. An elongated coil type spring 141 is wound about the pivot and has its arms respectively engaging the levers 137 and 138 tending to straighten them. The coil spring 141 may be precompressed to any desired extent and a stop pin 142 is preferably provided on the lever 137 to engage the lever 138 and limit straightening movement of the levers in response to the spring.

The lever 137 carries a pin 143 at its free end which engages the upper end of the latch lever 131. The upper end of the latch lever is shaped as explained in Figures 1-6 to provide relatively

light camming action tending to lift the latch handle 133 and disengage the latch.

The free end of the lever 138 carries a roller 144 which engages the cam plate 145 secured to the upper arm 119. The cam plate is so shaped that when the iron is in or near its lowered working position the turning effect of the compensating spring device on the upper arm 119 will be substantially constant through a relatively wide range of movement.

As shown in Figure 7, when the iron is in its raised position, the lever 138 is in engagement with the pin 142 so that the compensating spring device exerts no turning effect on the upper arm. As the arms are straightened during lowering of the iron, the spring device will be compressed by the cam and the spring 123 will be tensioned and will move toward the pivot 118 so that its effective force tends to decrease. After the roller 144 has moved over a corner 146 on the cam, it will engage the end cam surface, as shown in Figure 8, and will exert on the arm 119 a turning force opposing the spring 123. At this time, the raising force of the spring 123 is effectively cancelled so that the iron will remain on the work and will rest thereon with its full weight as long as the latch handle 133 is held down.

On releasing the latch handle 133 the latch lever 131 will swing away from the pin 143 allowing the compensating spring device to turn clockwise, thereby to remove its compensating force. At this time, the spring 123 will be effective to raise the iron.

In the event the iron should be lowered to an extreme position, as, for example, if it should drop from the edge of the board, the spring 123 would come so close to the pivot 118 that it might not have sufficient force to raise the iron. To prevent this possibility, a pin 147 is secured in the lower arm 115 in a position to engage the side of the spring 123 and bend it laterally, as shown in Figure 9. When the iron drops off the edge of the board or is otherwise moved to an extreme lowered position, the pin 147 will bend the spring 123 as indicated in Figure 9 so that the lateral deflecting force of the spring will be added to its tension effect to raise the iron. At the same time the cam 145 is so shaped that even though the latch handle 133 is held downward, the roller 144 will move out of engagement with the cam to eliminate the effect of the compensating spring device. Thus sufficient force will be provided through the tension and lateral bending effect of the spring 123 to raise the iron even from an extreme position.

Figures 7-9 illustrate another desirable feature which can be applied equally well to the construction of Figure 1. It is desirable in using the iron to maintain the supporting lever 121 substantially vertical at all times so that the iron will be properly balanced and can be turned during use. To maintain the lever properly vertical under all conditions, it is pivoted intermediate its ends on the pin 124 and has its lower end connected by a link 148 to the pin 125 in the vertical arm 115. The distance between the pivot 124 and the lower end of the link is the same as the distance between pivot 118 and pin 125, so that in effect a parallelogram linkage is provided to hold the lever 125 vertical regardless of the relative angular positions of the arms. In this way, the iron is maintained properly balanced at all times and still obtains the necessary freedom of movement through the joint member 122.

While two embodiments of the invention have

been shown and described in detail, it will be understood that they are illustrative only and are not intended to be a definition of the scope of the invention, reference being had for this purpose to the appended claims.

What is claimed is:

1. A support for an iron comprising a pair of arm members pivotally interconnected at one end, one of the members being formed at its other end for connection to an iron, means at the other end of the other member for connection to a support to support the members and the iron above an ironing board, a spring connected to the members urging them in a direction about their pivotal interconnection to raise the iron and means acting on the members to make the spring ineffective when the members are moved in a direction to lower the iron and a releasable latch carried by one of the members controlling the last named means.
2. A support for an iron comprising a pair of arm members pivotally interconnected at one end, one of the members being formed at its other end for connection to an iron, means at the other end of the other member for connection to a support to support the members and the iron above an ironing board, a spring connected to the members urging them in a direction about their pivotal interconnection to raise the iron, a second spring acting on the members in opposition to the first named spring, and a releasable latch carried by one of the members controlling the second spring to make it effective or ineffective.
3. A support for an iron comprising an iron having a handle, a first arm rigidly secured to the iron and projecting upward therefrom, a second arm pivoted to the upper end of the first arm, means at the free end of the second arm for connection to a support, a spring connecting the arms and urging the second arm toward a horizontal position to raise the iron, means acting on the arms to make the spring ineffective, a latch carried by one of the arms to make the last named means effective or ineffective and an operating lever for the latch pivotally connected to the first arm and lying adjacent to the handle of the iron.
4. A support for an iron comprising an iron having a handle, a first arm rigidly secured to the iron and projecting upward therefrom, a second arm pivoted to the upper end of the first arm, means at the free end of the second arm for connection to a support, a spring connecting the arms and urging the second arm toward a horizontal position to raise the iron, a second spring acting between the arms in opposition to the first named spring, a releasable latch carried by the first arm and latching one end of the second spring to make the second spring effective or ineffective, and an operating lever for the latch pivotally connected to the first arm and lying adjacent to the handle of the iron.
5. A support for an iron comprising a pair of arm members pivotally interconnected at one end, one of the members being formed at its other end for connection to an iron, means at the other end of the other member for connection to a support to support the members and the iron above an ironing board, a spring connected to the members urging them in a direction about their pivotal interconnection to raise the iron, a compression spring device connected at one end to one of the members to act in opposition to the first named spring, a movable

abutment on the other of the members engaging the other end of the compression spring device, and a releasable latch carried by the other of the members and engageable with the movable abutment to hold the movable abutment in operative position.

6. A support for an iron comprising a pair of arm members pivotally interconnected at one end, one of the members being formed at its other end for connection to an iron, means at the other end of the other member for connection to a support to support the members and the iron above an ironing board, a spring connected to the members urging them in a direction about their pivotal interconnection to raise the iron, an elongated coil spring having end portions offset from its axis to provide a substantially constant spring force regardless of the degree of compression thereof, one of the end portions being connected to one of the arm members to oppose the first named spring, a movable abutment on the other arm member engaging the other end portion, and a releasable latch on the other arm member to hold the movable abutment in operative position.

7. A support for an iron having a handle, comprising a first arm rigidly secured to the iron and projecting upward therefrom, a second arm pivoted to the upper end of the first arm, means at the free end of the second arm for connection to a support, a spring connecting the arms and urging the second arm toward a horizontal position to raise the iron, an elongated coil spring having end portions offset from its axis to provide a substantially constant spring force regardless of the degree of compression thereof, one of the end portions being connected to the second arm to act thereon in opposition to the first named spring, a movable abutment on the first arm engaging the other end portion, a latch on the first arm to hold the abutment in operative position, and an operating lever for the latch lying adjacent to the handle of the iron.

8. A support for an iron comprising a pair of arm members pivotally interconnected at one end, one of the members being formed at its other end for connection to an iron, means at the other end of the other member for connection to a support to support the members and the iron above an ironing board, a spring connected to the members urging them in a direction about their pivotal interconnection to raise the iron, a spring device resilient in compression mounted on one of the arm members, a releasable latch on said one of the arm members providing an abutment for one end of the spring device and a cam on the other arm member engaging the other end of the spring device and shaped to produce a substantially constant force on the members when they are moved in a direction to lower the iron opposing the first named spring.

9. A support for an iron having a handle, comprising a first arm rigidly secured to the iron and projecting upward therefrom, a second arm pivoted to the upper end of the first arm, means at the free end of the second arm for connection to a support, a spring connecting the arms and urging the second arm toward a horizontal position to raise the iron, a spring device resilient in compression, mounted on the first arm, a releasable latch on the first arm engaging one end of the spring device and providing an abutment therefor, an operating lever for the latch lying adjacent to the handle of the iron, and a cam

on the second arm engaging the other end of the spring device and shaped to produce a substantially constant force on the arms when they are moved in a direction to lower the iron opposing the first named spring.

10. A support for an iron comprising a pair of arms pivotally interconnected at one end, one of the arms being formed at its other end for connection to an iron, means at the other end of the other arm for connection to a support to support the arms and iron above an ironing board, a spring connected to spaced points on the arms respectively lying in a line at one side of the pivot connection between the arms and urging the arms to an angular position to raise the iron, the line between said points approaching the pivot when the arms are straightened to lower the iron thereby to decrease the effectiveness of the spring and means carried by and acting on the arms and including a latch to make the spring ineffective when the arms are straightened to lower the iron.

11. A support for an iron comprising a pair of arms pivotally interconnected at one end, one of the arms being formed at its other end for connection to an iron, means at the other end of the other arm for connection to a support to support the arms and iron above an ironing board, a spring connected to spaced points on the arms respectively lying in a line at one side of the pivot connection between the arms and urging the arms to an angular position to raise the iron, the line between said points approaching the pivot when the arms are straightened to lower the iron thereby to decrease the effectiveness of the spring, a second spring operatively connected to the arms to oppose the first spring with a substantially constant force when the arms are straightened to lower the iron, and a latch carried by one of the arms and engaging the second spring to make the second spring effective and releasable to make the second spring ineffective.

12. A support for an iron comprising a pair of arms pivotally interconnected at one end, one of the arms being formed at its other end for connection to an iron, means at the other end of the other arm for connection to a support to support the arms and iron above an ironing board, a spring connected to spaced points on the arms respectively lying in a line at one side of the pivot connection between the arms and urging the arms to an angular position to raise the iron, the line between said points approaching the pivot when the arms are straightened to lower the iron thereby to decrease the effectiveness of the spring, an elongated coil spring having its end portions offset from its axis, a releasable latch on one of the arms forming an abutment for one end portion of the spring, and the other end portion being connected to the other of the arms to exert a substantially constant force thereon opposing the first named spring when the arms are straightened to lower the iron.

13. A support for an iron comprising a pair of arms pivotally interconnected at one end, one of the arms being formed at its other end for connection to an iron, means at the other end of the other arm for connection to a support to support the arms and iron above an ironing board, a spring connected to spaced points on the arms respectively lying in a line at one side of the pivot connection between the arms and urging the arms to an angular position to raise the iron, the line between said points approaching the pivot when the arms are straightened to lower the iron

thereby to decrease the effectiveness of the spring, a spring device resilient in compression mounted on one of the arms, a releasable latch on said one of the arms forming an abutment for one end of the spring device, and a cam on the other arm engaging the other end of the spring device and shaped to produce a substantially constant force on the arms opposing the first named spring when the arms are straightened to lower the iron.

14. A support for an iron comprising a pair of arms pivotally interconnected at one end, one of the arms being formed at its other end for connection to an iron, means at the other end of the other arm for connection to a support to support the arms and iron above an ironing board, a spring connected to spaced points on the arms respectively lying in a line at one side of the pivot connection between the arms and urging the arms to an angular position to raise the iron, the line between said points approaching the pivot when the arms are straightened to lower the iron thereby to decrease the effectiveness of the spring, and a part on one of the arms to engage the spring and deflect it laterally from a line between the points when the arms are straightened to lower the iron to an extreme lowered position thereby to increase the effectiveness of the spring.

15. A support for an iron comprising a pair of arms pivotally interconnected at one end, one of the arms being formed at its other end for connection to an iron, means at the other end of the other arm for connection to a support to support the arms and iron above an ironing board, a spring connected to spaced points on the arms respectively lying in a line at one side of the pivot connection between the arms and urging the arms to an angular position to raise the iron, the line between said points approaching the pivot when the arms are straightened to lower the iron thereby to decrease the effectiveness of the spring, a part on one of the arms to engage the spring and deflect it laterally from a line between the points when the arms are straightened to lower the iron to an extreme lowered position thereby to increase the effectiveness of the spring, and means including a latch carried by and acting on the arms to make the spring effective or ineffective.

16. A support for an iron comprising a pair of arms pivotally interconnected at one end, one

5

10

of the arms being formed at its other end for connection to an iron, means at the other end of the other arm for connection to a support to support the arms and iron above an ironing board, a spring connected to spaced points on the arms respectively lying in a line at one side of the pivot connection between the arms and urging the arms to an angular position to raise the iron, the line between said points approaching the pivot when the arms are straightened to lower the iron thereby to decrease the effectiveness of the spring, a part on one of the arms to engage the spring and deflect it laterally from a line between the points when the arms are straightened to lower the iron to an extreme lowered position thereby to increase the effectiveness of the spring, a second spring operatively connected to the arms to oppose the first named spring when the arms are straightened to lower the iron, and a releasable latch carried by one of the arms and connected to the second spring to make it effective or ineffective.
